UNITED STATES PATENT OFFICE.

BASIL G. AUSTIN, OF HARTFORD, CONNECTICUT, ASSIGNOR TO AUSTIN ORGAN COMPANY, OF HARTFORD, CONNECTICUT, A CORPORATION OF MAINE.

ORGAN-PIPE.

1,097,506.

Specification of Letters Patent.

Patented May 19, 1914.

Application filed September 25, 1913. Serial No. 791,789.

To all whom it may concern:

Be it known that I, BASIL G. AUSTIN, a citizen of the United States, residing at Hartford, in the county of Hartford and State of Connecticut, have invented certain new and useful Improvements in Organ-Pipes, of which the following is a specification.

This invention relates to organ pipes, among the objects of the invention being the provision of simple and effective means by which the formation of eddy currents therein is avoided to thus prevent "windiness" as it is known and also by which the amount of air to be supplied can be accurately and precisely regulated by virtue of which latter point the volume of sound can be governed or adjusted.

In the drawings accompanying and forming part of the present specification I have shown in detail two of the many forms of embodiment of the invention which to enable those skilled in the art to practise the same will be set forth fully in the following description. I may depart in several respects from the disclosure thus made within the scope of the invention defined by the claims following said description.

Referring to said drawings: Figure 1 is a sectional side elevation of a metal pipe embodying my invention. Fig. 2 is a similar view of a wooden pipe equipped with the invention in a slightly different form.

Like characters refer to like parts in both figures.

As will be inferred from what has already been stated the invention comprises two features, one by which the formation of eddy currents in an organ pipe is prevented, and the other by which the intensity of sound can be varied, and these can be employed separately, although in both forms of the device, one means secures both results.

In Fig. 1 the numeral 2 denotes the lower portion of a metal organ pipe, the foot 3 of which is downwardly tapered after the usual fashion, said pipe having in the lower part of its foot the air inlet port 4 and having in its body the mouth 5 below which is disposed the customary languid 6. I provide means for dividing the air which enters the pipe by way of said inlet port 4 or otherwise, into a multiplicity of streams or jets, by reason of which eddying of the air with-

in the foot of the pipe or below the languid 6 is not possible, and the means by which this result can be obtained may vary as to character, two different forms being shown herein, one especially well adapted to the metal pipe shown in Fig. 1, and the other to the wooden pipe illustrated in Fig. 2. Referring again to Fig. 1 the numeral 7 designates a cylinder which as shown is integral with the foot 3, and which rises from the port 4. This cylinder has in it a large number of perforations or holes 8. It, therefore, follows that the air by which the pipe 2 is made to speak, must pass through some or practically all these openings, the result being that the air is delivered as already intimated, into the pipe in a large number of jets or streams. In like fashion various means may be provided for regulating the amount of air. As shown the cylinder 7 contains an adjustable cylindrical plug 9 which can be made of wood or other suitable material and which comparatively closely fits the interior of said cylinder but which is capable of relative free movement up and down therein and by which certain of the perforations of the cylinder 7 can be thrown into and out of use.

In Fig. 1 the plug 9 constituting a suitable valve is shown as being substantially midway of the height of the cylinder or tube 7, the consequence being that the air which enters the port 4 cannot pass through the perforations 8 covered by the plug 9 or through those above said plug but can only go through the perforations below the plug. By moving the plug up or down the number of perforations which are to be used can be increased or decreased to correspondingly vary the amount of volume of sound of the pipe. If the amount of air entering the pipe be considerable the tone will be heavy, while if the plug be lowered the tone will be lighter. Fastened to the plug 9 and rising therefrom is the elongated stem 10 which extends through a guide hole or opening in the languid 6 and which at its upper end is equipped with a button or like operating part which can be grasped to move the stem 10 longitudinally and thereby effect the elevation or lowering of the plug 9. It will be seen that the button or equivalent portion 11 of the stem is readily accessible, owing to the fact that it is

opposite the mouth 5 and it can be reached by the hand or a suitable tool to adjust the plug 9, which is a feature of advantage. The stem 10 can be continued below the plug 5 and formed into a hook 10' so that the plug can also be shifted from below the pipe 2.

In Fig. 2 the organ pipe 12 is of wood, and its foot constituting a suitable valve as will hereinafter appear is denoted by 13, the 10 open lower end of said foot presenting a port for the entrance of air into said pipe, the languid of which is designated by 14 and the mouth by 15. In the upper portion of the foot 13 is a perforated metallic cylinder 16 closed at its upper end. To said closed upper end is connected the shank or rod 17 projecting through a guide hole in the languid 14 and having a button 18 which can be reached by the hand or a suitable implement passed through the mouth 15 to effect raising or lowering of the perforated cylinder 16. By raising or lowering said cylinder 16, the perforations therein can be more or less covered by the foot 13 to vary 25 the amount of air passing into the pipe 12. In similar fashion this cylinder 16 divides the air into a large number of jets. The stem 17 can also be extended downward as at 17' to provide for the adjustment of the 30 cylinder 16 below the pipe 12, the lower end of the extension 17' terminating in a hook to facilitate changing the position of said cylinder.

What I claim is:

35 1. An organ pipe having a languid, an air inlet port, and means between the port and said languid, for directing air into said pipe

in a multiplicity of jets, said means being spaced from said languid.

2. An organ pipe combined with means 40 comprising a perforated cylinder for directing the air in jets into the pipe, and means whereby the amount of air thus delivered can be varied.

3. An organ pipe having an air inlet 45 port, a perforated cylinder connected with said port through the perforations of which air passes into the pipe, and a plug adjustable in the cylinder and movable to regulate the amount of air entering the pipe. 50

4. An organ pipe having a languid and an air inlet port, a perforated cylinder connected with said port and by which the air is divided into jets for supply to the pipe in such condition, a plug in said cylinder adjustable to regulate the amount of air entering the pipe, and an operating rod connected to said plug and extending through said languid, the pipe having a mouth opposite the upper portion of said rod. 55

5. An organ pipe having a perforated cylinder for directing air in jets thereinto, and a valve for said perforated cylinder, the perforated cylinder and valve being relatively movable to vary the amount of air to be delivered into said pipe. 60

In testimony whereof I affix my signature in presence of two witnesses.

BASIL G. AUSTIN.
